R. S. JACOBSEN,
GRADING OR SCREENING MATERIALS.
APPLICATION FILED JUNE 13, 1917.

1,403,326.

Patented Jan. 10, 1922.

UNITED STATES PATENT OFFICE.

RICHARD S. JACOBSEN, OF CHICAGO, ILLINOIS, ASSIGNOR TO JACOBSEN & SCHRAEDER, INCORPORATED, OF CHICAGO ILLINOIS, A CORPORATION OF ILLINOIS.

GRADING OR SCREENING MATERIALS.

1,403,326.

Specification of Letters Patent. Patented Jan. 10, 1922.

Application filed June 13, 1917. Serial No. 174,453.

To all whom it may concern:

Be it known that I, RICHARD S. JACOBSEN, a subject of the King of Norway, residing in Chicago, in the county of Cook and State 5 of Illinois, have invented a certain new and useful Method of Grading or Screening Materials, of which the following is a specification.

This invention relates to a novel and useful method of grading or screening coal, stone and other granular materials.

It is especially applicable to coal mining plants, in connection with or as a part of the tipple for preparing and efficiently grad- 15 ing or screening the coal.

One of the objects of my improved method is the provision and arrangement of means for grading or screening materials whereby the largest pieces of the material are first 20 extracted from the mass and then the next larger in size and so on until all of the material has been separated or graded and deposited where desired.

The advantages of my herein described 25 method are several and far-reaching. In one instance, and particularly in the handling of fragile material as coal, it will be observed that my method is opposite to that now generally employed by the present coal 30 tipple arrangements wherein the practice is to remove or extract by screening, the smallest sizes first, and finally to discharge the lump at the ends of such screens. It will be observed that in this present practice, the 35 larger sizes of coal are carried over the greater portion of the screening surface and that particularly the lump traverses the entire screens before final disposition. Among the objectionable results of this practice are 40 the undesirable further crushing of the smaller materials under the rolling or screening action of the larger, the disadvantage of picking the mixed coal to extract the refuse, such as rock or slate, and further, the re- 45 duction of the effective screening surface by the unnecessary transportation of the larger sizes toward the farther end of the screen.

The present invention contemplates also 50 and provides a novel arrangement of conveying screens tending toward a variation of tipple design affording very efficient arrangements meeting a variety of conditions and requirements so often desired in the grading of coal.

With these and other objects in view, this 55 invention resides in the method herein described, and in the combination, arrangement, and relative positions of the parts and members set forth in the following specification, and particularly pointed out and fall- 60 ing within the scope of the appended claims.

In the diagrammatic drawings, Figure 1 is a sectional elevation of a system of screens and conveyors arranged in accordance with my novel method.

Figure 2 is a plan view and Figure 3 is a 65 sectional elevation taken on line 3—3 of Figure 1, showing the horizontal cross conveyor and pivoted chute for delivering the material into a railroad car.

Figure 4 is a preferred form or modification of the arrangement shown in Figure 3. In this case the chute is reciprocated by a similar mechanism mounted on the same shaft for the purpose of counteracting the 75 reaction of the coating horizontal conveyor and for affording a steeper angle for the chute by the opposite or retarding action induced by the oppositely mounted mechanism.

I have preferred to illustrate my invention as practiced in connection with horizontal screens and conveyors for grading coal, and as shown on the attached drawing, 10, indicates a delivery chute into which the coal is fed preferably with a regular pre- 80 determined rate by means of any suitable feeding device. In this particular instance, the screening or grading apparatus consists of a pair of substantially horizontal troughs, 11 and 12, which are supported respectively 85 on rollers, 11^A and 12^A and which are moved by means of a suitable mechanism with a peculiar reciprocatory motion so that the material supported or carried thereon will be conveyed in a forward direction. A 90 mechanism of this character is shown in my pending application for Letters Patent filed September 11, 1916, Serial No. 119554. Suitable connecting rods, 13, (partly shown) 95 are used to connect the mechanism with the 100 trough.

The mixed mass of coal is initially dis- 105 charged upon the upper deck of screen 11 which comprises the short sections of plate 11^B and 11^C, side plates 11^E and a plurality of parallel bars 11^D spaced sufficiently apart to pass all smaller sizes of coal and retain the predetermined size of lump, which it

will be observed, will be deposited onto the horizontal cross conveyor 14, and down the pivotally mounted inclined chute, 15, into the coal car, 16.

5 The mass of coal passed through the bars 11^D falls partly on the plate 11^F and parallel bars 11^G, which in this case are spaced shorter distances apart than the bars 11^D, thus retaining the next larger or egg size 10 and conveying same over the end plate 11^H onto the horizontal cross conveyor 17, which in turn discharges same down chute 18 into the car 19. The mixed coal which has passed between bars 11^G falls partly onto the solid plate 12^B and partly onto the perforated plate portions 12^C; here the coal is further rescreened, the next larger or nut coal being conveyed over the solid plate portion 12^D to be passed down a suitable 15 chute 20 into car 21. The under-size or slack which has passed through the round perforations of 12^C falls onto the lower deck solid plate 12^E and is conveyed into chute 22 to the car 23. The supporting rollers 24 20 and driving mechanisms 25 for the cross conveyors are similar to those above described for the screens. The plates 11^G and 11^H are deflected downwardly as at 26 to slightly lift the coal as it passes same to 25 prevent clogging of screen by coal which might otherwise engage the sharp edge of the plate.

It is obvious that in both cases where I have provided bars, plates with large 30 perforations could be used; I prefer to show bars. It is also apparent that the cross conveyors provide opportunity for picking the screened coal to remove refuse as rock and slate, and that such cross conveyors could, 35 if desired, be used in connection with the other sizes.

From the foregoing it will be seen that the screening apparatus comprises a plurality of horizontally disposed and endwise reciprocating screens, the reciprocation of which is necessary in order to advance the materials thereon, inasmuch as it is desired to keep the height of the apparatus as low as possible, instead of tilting the screens to advance the materials thereon by gravity. 40 The transversely arranged conveyors 14 and 17 receive the materials from the discharge ends of the reciprocating screens, and are also horizontally disposed, so that the reciprocation of these conveyors is also necessary in order to advance the materials thereon. With this arrangement, therefore, the materials are advanced intermittently on the screens, in the manner explained, and are 45 also advanced intermittently on the transversely arranged conveyors, so that in time the coarser materials which stay on each screen are discharged from the end thereof, and are then finally discharged from the end

of the corresponding transverse conveyer. 65 In the sizing or grading of coal, especially soft coal, it is desirable to eliminate or separate the coarser portions first, so that the large pieces are not carried on the screening apparatus for more than a short 70 period of time, thus minimizing the breakage of the coal, and reducing the amount of slag or fine stuff. Therefore, as explained, the coarse materials are eliminated first, so that the materials are graded from 75 coarse to fine, and the reciprocation of the apparatus, which is necessary to advance the materials thereon, serves also to agitate the coal or other materials to cause the different sizes to drop through the perforations or 80 openings or meshes of the screens. Even the chutes 15 and 18 are adapted to operate horizontally, as they are provided with mechanism, as shown, to produce the reciprocation necessary to advance the materials 85 thereon, and thus the feeding of the materials by gravity is practically entirely eliminated from the operation of the apparatus, and at the same time the materials are graded from coarse to fine, so that the 90 coarser materials are almost immediately allowed to escape from the apparatus, thus insuring the proper sizing or grading of the coal in a manner that involves practically 95 a minimum of breakage.

With the foregoing process or method of screening and grading materials, it will be seen that the coarsest materials are formed into a heap in the car 16, the next size into a heap in the car 19, the next size into a heap in the car 21, and the finest size into a heap in the car 23, so that the finest size forms the third heap in the series of four heaps thus formed by the screening and grading of the materials. The screen 11^G extends under the 105 screen D, and the screen 12^C extends under the screen 11^G, so that the latter must extend under the endwise reciprocating and transversely arranged conveyer 14, while the screen 12^C extends under the endwise reciprocating and transversely arranged conveyer 17, thus requiring a horizontal and lateral discharge of the first two sizes from the longitudinally disposed screening apparatus. 110 On the other hand, there is nothing below the discharge end of the conveyer 12^E, and nothing below the discharge end of the conveyer section 12^D, so far as screens or other conveyers are concerned, and hence any ordinary or suitable spouts 20 and 22 can be used 115 to receive the materials at these points, as the discharge can be directly downward or more or less in a downward direction, if so desired, whereas the materials discharged into the conveyers 14 and 17 would have to pass downwardly through other screens, should a direct downward discharge be attempted, and hence the desirability of the direct lateral 120 125

discharge afforded by these two endwise reciprocating and transversely arranged conveyers.

Having thus described my invention, what I claim as new is:

1. A screening apparatus comprising a horizontally disposed screen, means whereby said screen reciprocates longitudinally to advance the materials thereon from one end thereof to the other, so that the coarser portions of the materials stay on the screen and are discharged from one end thereof, while the finer materials fall through the screen, a transversely arranged conveyer to receive 10 the coarser materials, and mechanism to reciprocate said conveyer endwise to advance the materials thereon and finally discharge the same from the end thereof.
2. A structure as specified in claim 1, in combination with a second reciprocating screen arranged below said first screen, a second transverse conveyer arranged to receive the discharge from the end of the second screen, and mechanism for reciprocating 25 the second conveyer endwise.
3. A structure as specified in claim 1, in combination with screening apparatus arranged to receive the materials which fall through said reciprocating screen.
4. The combination of a plurality of endwise reciprocating screens so arranged that the finer materials pass through one screen while the coarser materials remain thereon and are discharged from the end thereof onto 35 the next screen, means to receive the materials from the ends of said screens, and means to receive the finer materials which fall through the last screen, said screens being disposed horizontally, so that the reciprocating movement of the screens is necessary for the advancement of the materials thereon, and said means for receiving the materials from the ends of said screens comprising one or more transversely arranged 40 and endwise reciprocating conveyers which are also horizontally disposed.
5. A screening apparatus as specified in claim 1, said transversely arranged conveyer being provided with a tilting chute for discharging the materials therefrom, the screen and the conveyer being reciprocated independently of each other.
6. In screening apparatus, the combination of screening instrumentalities comprising one or more endwise reciprocating and horizontally disposed screens, said apparatus having openings therein to eliminate the coarser materials first, so that the materials are graded from coarse to fine, operating 55 mechanism to produce the longitudinal reciprocation of said apparatus to intermittently advance the materials thereon, as well as to agitate the materials, so that all of the materials except those which remain on
- the screen fall through and are received by 65 the next screen, and means for separately and laterally discharging the sized materials from said screening instrumentalities, each screen being substantially horizontal, and said laterally discharging means being 70 also substantially horizontal, together with mechanism for operating said discharging means independently of the operation of said screening instrumentalities.
7. In a screening apparatus, the combination of a horizontally disposed and longitudinally reciprocating structure comprising screening instrumentalities for eliminating the coarser materials first, so that the materials are graded from coarse to fine, 75 means for separately discharging the sized materials from the screening instrumentalities, and mechanism for producing the longitudinal reciprocation of said apparatus.
8. In a screening apparatus, the combination of a screen, a transversely arranged and endwise reciprocating conveyer to receive the coarse materials from the end of the screen, and a screen extending under 80 said conveyer to receive the materials which pass through the perforations of said first mentioned screen.
9. In a screening apparatus, the combination of a screen, a transversely arranged and endwise reciprocating conveyer to receive 85 the coarse materials from the end of said screen, and a longitudinally arranged and endwise reciprocating conveyer extending under said first mentioned conveyer to receive the materials which pass through the 90 perforations of said screen.
10. A structure as specified in claim 8, said screens having endwise reciprocation to intermittently advance the materials thereon.
11. The combination of a screen, an endwise reciprocating and transversely arranged conveyer to receive the coarse materials from the end of said screen, and means extending under said conveyer to receive the materials which pass through the 105 perforations of said screen.
12. In screening apparatus, the combination of a series of longitudinally disposed and endwise reciprocating screens disposed 110 in different horizontal planes, so that the materials which pass through the perforations of one screen are received by the next screen, mechanism for reciprocating said screens to intermittently advance the materials thereon, so that the advancement of the materials on each screen is dependent entirely upon the reciprocation thereof, and means for receiving and grading the materials below the screens.
13. In screening apparatus, the combination of means for forming the coarse materials in a heap, means for forming some 120

of the finer materials in another heap, and means for accumulating the finest materials in a heap between said other heaps.

14. In screening apparatus, the combination of means for forming the coarsest materials into a heap, means for forming the finest materials into another heap, means for forming another size of the materials into a heap between said other heaps, and means for forming still another size of the materials into a heap beyond the said finest heap.

15. The process of grading materials, which consists in forming the coarsest materials into a heap, forming the next size into another heap, then forming the finest materials into a third heap, and finally accumulating an intermediate size into a fourth heap.

20 16. In screening apparatus, the combination of a plurality of transversely arranged and endwise reciprocating conveyers, so that the materials are successively screened and discharged laterally from the apparatus,

and horizontally operating conveying means 25 extending under said endwise reciprocating conveyers.

17. A structure as specified in claim 16, in combination with an endwise reciprocating screen also extending under each of said 30 endwise reciprocating conveyers.

18. The process of screening and grading materials, comprising the forming of the coarsest materials into a heap, the forming of the finest materials into another heap, the 35 forming of an intermediate size of said materials into a third heap, and finally forming another size into a fourth heap, so that the coarsest size forms the first heap, the next size the second heap, the next size the 40 fourth heap, and the finest size the third heap in the series of four heaps thus formed by the screening and grading of the materials.

In witness whereof, I have hereunto subscribed my name this ninth day of June, 1917.

RICHARD S. JACOBSEN.
